UNITED STATES PATENT OFFICE.

WILLIAM A. READY, OF BROOKLINE, MASSACHUSETTS.

DESIGN FOR A PANEL FOR RADIODIALS.

Application filed February 15, 1926. Serial No. 16,522. Term of patent 7 years.

To all whom it may concern:

Be it known that I, WILLIAM A. READY, a citizen of the United States, residing at Brookline, in the county of Norfolk and State of Massachusetts, have invented a new, original, and ornamental Design for Panel for Radiodials, of which the following is a specification, reference being had to the accompanying drawing, forming a part thereof.

The figure of the drawing is a perspective view of a panel for radio dials showing my new design.

I claim:

The ornamental design for a panel for radio dials as shown.

WILLIAM A. READY.
